BRAKE-CONTROL AND SIGNAL SYSTEM FOR SINGLE-TRACK RAILWAYS.

1,169,516.

Specification of Letters Patent. Patented Jan. 25, 1916.

Application filed October 17, 1913. Serial No. 795,675.

To all whom it may concern:

Be it known that I, PETER SCHNEIDER, of Oswego, in the county of Oswego, in the State of New York, have invented new and useful Improvements in Brake-Control and Signal Systems for Single-Track Railways, of which the following, taken in connection with the accompanying drawings, is a full, clear, and exact description.

10 This invention relates to certain improvements in automatic brake-setting apparatus for railway-block systems and may be used in connection with certain forms of electrically operated block signals which are maintained in their inoperative positions by normally closed circuits connected with the rails and adapted to be released to their operative positions at opposite ends of each block by short circuiting of the signal-operating circuits through the medium of the axles of an engine, train or car which may enter that particular block for the purpose of setting signals against the entrance of other engines, trains or cars from either end of such block.

20 25 when any of the rolling stock is stationed therein or passing therethrough.

It sometimes happens from various causes that the driver of the motor will fail to observe a block signal which is set against him and will, therefore, enter a block at greater or less speed when another train is present therein, resulting in loss of life and damage to property by collision.

It is well known that practically all engines or motor cars are equipped with suitable valves for setting the air brakes on the engine and throughout the several cars of a train in order to stop the train abruptly in case of emergency, and the primary object 35 of my invention is to provide means for automatically operating the emergency brake-controlling valve on an engine, car or train which may be about to enter either end of a block in which another engine, car or train 40 is located so as to set the brakes upon and stop such approaching train before entering that block.

Other objects and uses will be brought out in the following description.

50 In the drawings Figure 1 is a diagrammatic view of a portion of a railway divided into blocks, electrically operating block signals therefor, and portions of the electrical apparatus adapted to coöperate with certain 55 mechanism carried by the engine or other parts of the train for operating the engi-

neer's brake valve. Fig. 2 is a detail view of the valve-operating member carried by the engine and one of its coacting devices located alongside of the track in the path of 60 said member. Fig. 3 is a diagrammatic view of a semaphore signal and its operating magnet.

In order that my invention may be clearly understood, I have shown a portion of a 85 railway track —1— divided into blocks of auy suitable length, the ends of the rails of each block being insulated from each other by insulation —2— so that the rails of each block may be separately energized from a 70 suitable source or sources of electric energy as batteries —3— which are connected by wires —4— and —4'— across the rails.

Separately operated pairs of electric signals —5—, —5'—, —6—, —6'—, and —7— 75 and —7'— are suitably installed in conspicuous places in proximity to the ends of each block so as to be clearly visible by the drivers of motors along the track in either direction and, therefore, the signals of each pair are 80 arranged to face in opposite directions in the direction of length of the track, the signal facing each block being electrically connected by wires —8— across the rails of the next adjacent block. It, therefore, follows 85 that when no car or train is present in any of the blocks, the signal circuits for such blocks will be normally closed, thereby energizing the signals —5—, —5'—, —6—, —6'—, —7— and —7'— to normally hold them in 90 their inoperative positions, but on the other hand as soon as a train enters any one of the blocks, one or more of the axles which are usually made of steel or some electrical conducting material together with the 95 wheels mounted thereon will short circuit the signal circuits for adjacent blocks, thereby releasing the signals such as semaphores and allowing them to gravitate to their operative positions to warn the drivers of any 100 train which may approach from either end of the block that the block is already occupied.

In Fig. 3, I have shown diagrammatically one of the signals as having a weighted semaphore arm —9— pivoted at —10— to a suitable support and connected to the core or plunger of a solenoid —11— which is normally energized when no cars are present in the blocks to hold the semaphore —9— in its 105 operative position but, as previously stated, as soon as any signal circuit is short cir-

cuated by the presence of a car or train in one of the blocks, the solenoid or magnet —11— will be deenergized sufficiently to allow the weighted semaphore —9— to drop to its operative position shown by dotted lines.

In Fig. 1, I have shown diagrammatically a series of two complete blocks and portions of additional blocks at the ends thereof and these blocks may be designated as —A—, —B—, —C— and —D— and for convenience of illustrating the operation of my invention, I have shown by dotted lines a car axle —E— representing a car or train in the block —B—, thereby short circuiting the electric circuits leading respectively to the electric signals —5— and —6'— to deenergize their respective magnets and allow the corresponding semaphores to drop to their operative positions to protect the train in that particular block against the entrance of other trains from either end thereof, the corresponding signals of each block being similarly set by cars or trains which may enter the same. It is evident, however, that as the train passes out of any block, as for example the block —B—, the corresponding signals —5— and —6'— will be reenergized to restore their respective semaphores to their inoperative positions. These signaling devices and their respective electro circuits are shown more particularly to illustrate the use of my invention in connection therewith so as to obviate the necessity of installing a separate electrical system for the several devices employed in connection with the automatic brake-setting mechanism hereinafter more fully set forth.

I preferably employ separate sets of brake-setting mechanisms one for each end of each block, each set comprising separate electromagnets —15— and —16— and corresponding armatures —17— and —18—, the electromagnet —15— for the end of each block being connected by wires —19— to the signal circuit for the next adjacent block and it, therefore, follows that this magnet will be energized from the signal circuit when no car is present in the corresponding block, thereby attracting and holding its armature —17— in a predetermined position.

As illustrated in Fig. 1 of the drawings, each armature —17— is made in the form of a lever and fulcrumed at —20—, having a heel —21— normally engaged with one of the members of an electric switch —22— for normally closing said switch which when released is self-opening and may be of any well known type adapted for this purpose.

Each electric switch —22— is connected in a separate electric circuit —24— having preferably a separate source of electric energy —25— and including therein the electromagnet —16— which is, therefore, normally energized to attract its armature

—18— and hold it in a predetermined position. This armature is connected to one end of a rock shaft —25— carrying at one end a ratchet wheel —26— and at its other end a rock arm or brake-controlling member 70 —27—.

The rock shaft —25— may be supported in any suitable manner not necessary to herein illustrate or describe for supporting the rock arm —27— along the outer side of the track, but in close proximity thereto for engagement by a valve operating member —30— which is mounted on the engine in such manner as to engage and operate the engineer's brake valve as —31— when the rock arm —27— is set by the entrance of a car or train in the corresponding block.

It is now clear that the electromagnet —15— will be deenergized simultaneously with the deenergizing of the corresponding signal magnet by the entrance of a car or train in that particular block and this deenergizing of the magnet —15— will release its armature —17— and thereby allow the corresponding switch —22— to open for 90 breaking the circuit —24— and thus deenergizing the electromagnet —16—. This deenergizing of the magnet —16— releases its armature —18— which is weighted sufficiently to rock the shaft —D— and thereby adjust the brake-controlling member —27— to an inclined position as shown in Fig. 2 in the path of the lower end of the valve operating member —30—, so that when this block is occupied by a car or train and another car or train seeks to enter that block through the failure of the driver to observe the signal set against him, the lower end of the valve-operating member —30— on the engine will ride against the inclined brake-controlling member —27— which in turn will effect a rocking movement of the valve-operating member sufficient to open the engineer's brake valve —31— and thereby apply the brakes throughout the train for automatically stopping the same before entering such block.

The free end of the armature —17— constitutes a locking pawl which when released by the deenergizing of the magnet —15— drops by its own gravity into locking engagement with the ratchet wheel —26— to positively hold the member —27— in its inclined position in the path of the lower end of the valve-operating member —30—. 115 As illustrated in Fig. 2, this valve-operating member is made in the form of a bell crank lever pivoted at —32— to any suitable support on the engine and has its lower end provided with a roller —33— for traveling contact with the brake-controller —27— where the latter is adjusted in the manner previously described. The upper end of this bell crank lever is provided with a counterweight —34— to return it to its normal position 120 130

after operating the valve —31—. This operation of the engineer's brake valve will, of course, stop the train before entering a block in which another car or train is located or 5 through which it is moving and after the train is brought to a stop automatically, the engineer or driver has simply to return the valve —31— to its normal position. On the other hand, if a train is in a block and another train has been stopped at the approach 10 of such block, the approaching train will have caused the setting of the signals against the train in the first named block and will also have adjusted the automatic brake-setting device as the contact member —27— so 15 that as the first named train attempts to leave its block with the approaching train ahead of it, its valve-operating member —30— will contact with the member —27— before 20 leaving such block and thereby operate the engineer's brake valve to bring such train to a stop, thus giving positive notice to both engine drivers that something is wrong ahead and with the result of an investigation and readjustment of the trains to 25 enable them to pass each other.

I have shown the separate sets of brake-setting apparatus for opposite ends of each block at opposite sides of the track, one 30 set for trains moving in one direction and the other set for trains moving in the opposite direction although it is evident that they may be located at the same side of the track and the valve-operating mechanism 35 properly located on the engine to contact with their coöperative contacts —27— in case the latter are automatically adjusted for use in the manner previously described to avoid collision.

40 It is believed that the construction and operation of my invention has been set forth with sufficient clearness and exactness to enable anyone skilled in the art to make and use the apparatus, and while I 45 have shown a specific form of brake-setting mechanism, it is evident that various changes may be made in the details of construction without departing from the spirit of this invention so long as the block system is provided with automatically operated contacts one at each end of each block 50 for engagement by a suitable operating member on the engine or motor car for operating the engineer's brake valve and thereby automatically setting the brakes of the car or train in case one car or train seeks to 55 enter a block in which another train is present.

What I claim is:

60 1. In a brake-control and signal system for single track railways, the combination of a track divided into blocks insulated from each other and separate energizing circuits

connected across the rails of the several blocks, separate pairs of electrically controlled signals at adjacent ends of the blocks for trains moving in opposite directions, the signal facing each block being electrically connected across the rails of the next adjacent block, separate pairs of movable brake-controlling members in the several blocks, 65 each self-adjustable to its operative position, one pair for each block for trains moving in opposite directions, separate local electric circuits, one for each brake-controlling member, each local circuit including therein a self-opening electric switch and an electro-magnet normally holding the brake-controlling members in their inoperative positions, 70 separate electrical devices, one for each switch connected across the signal-controlling circuits for normally closing the switches, each of said devices being rendered inoperative by the short circuiting of the block circuit through the presence of a car therein, 75 thereby allowing the corresponding switch to open the adjacent local circuits for de-energizing the magnets corresponding to the opened local circuits and allowing the corresponding brake-controlling members to assume their operative positions, and means 80 actuated by each opened switch for locking the brake-controlling member in its operative position.

2. In a brake-control and signal system for 90 single track railways, the combination with a single track electrically energized railway divided into blocks insulated from each other, each block having associated therewith separate brake-controlling members for 95 trains moving in opposite directions and separate local electric circuits, one for each 100 brake-controlling member, each local circuit including therein means for normally holding the corresponding brake-controlling member in its inoperative position, and a self-opening electric switch, separate electro-magnetic devices for said switches, each 105 electrically connected across the rails of the next adjacent block, whereby when a car is present in that block it will short circuit the corresponding rails and thereby de-energize such switch-holding magnet to allow the 110 opening of the switch and consequent opening of the corresponding local circuit to release the adjacent brake-controlling member, and coöperative means between each 115 switch and its brake-controlling member for locking the latter in its operative position when the switch is opened.

In witness whereof I have hereunto set my hand this 8th day of October, 1913.

PETER SCHNEIDER.
